UNITED STATES PATENT OFFICE.

FRIEDRICH LUDWIG BARTELT, OF BRISLINGTON, BRISTOL, ENGLAND.

WASHING OR DISINFECTING FIBROUS MATERIALS.

No. 906,091.

Specification of Letters Patent.

Patented Dec. 8, 1908.

Application filed May 18, 1907. Serial No. 374,511.

To all whom it may concern:

Be it known that I, FRIEDRICH LUDWIG BARTELT, soap and chemical manufacturer, a subject of the King of Great Britain, and 5 resident of 3 Kensington Place, Brislington, Bristol, England, have invented new and useful Improvements Relating to Washing or Disinfecting Fibrous Materials, of which the following is a specification.

10 The present invention has reference to the washing of linen, woolen, silk and cotton goods such as wearing apparel and unmade piece goods, household linen, etc. By washing is meant the operation or operations such 15 as take place in laundries where goods for the purpose of being cleansed are immersed and agitated in an aqueous washing solution contained in a tank or vessel. The washing alluded to has no reference whatever to dry 20 cleaning or disinfecting performed in a closed chamber by means of volatile substances or vapors. The solution used in washing is generally heated and contains saponaceous material for cleansing the goods and making 25 a lather when the solution is agitated. In some cases chemicals, spirits, or oils of a volatile nature are employed in the washing solution. These substances are intended to act on the goods but do not do so efficiently 30 for various reasons and require the addition of soap for producing a lather. Moreover, it is not economical to mix the chemicals, spirits, or oils with the rest of the solution.

I have discovered that I can produce better results by introducing into the hot aqueous washing solution, a detergent in the form of vapors of volatile substances mixed with air. The action of this mixture will be thoroughly efficient in attacking the dirt contained in the goods and in forming a lather without the aid of soap or saponaceous matters which are now employed.

According to my invention I pass atmospheric air over the volatile substance which 45 gives off the vapor required so that the air takes up and mixes with the vapor in question. The mixture is then forced into the washing solution which being in agitation it permeates throughout, acting on the goods 50 therein and making when hot a good lather.

In the accompanying drawing I have shown in sectional elevation, apparatus for passing atmospheric air over a vapor yielding liquid by means of which the air becomes charged,

and forcing the same charged with vapor into 55 a washing machine of the ordinary type.

a is a tank within which is a rotating cage for containing the materials to be washed. *b* is a shaft upon which the said cage is mounted.

c is a toothed wheel keyed on the shaft *b*.

d is an inlet pipe for water or solution.

e is a steam inlet pipe.

Near the washing machine, preferably on the same base, is an air pump *f*, driven by 65 means of a crank disk *g* on a shaft *h* which has a pinion *i* engaging with the toothed wheel *c*. This arrangement enables the pump and washing machine to work synchronously and stop simultaneously. If 70 preferred, a rotary instead of a reciprocating pump may be employed. The pump casing is in communication with a receptacle *j* adapted to contain the vapor giving material. In the present instance a liquid is indicated. This receptacle is open to the pump casing at *k* and to the atmosphere at *l*. Air for feeding the pump is drawn from the inlet *l* over the contents of the receptacle *j*, through the pump casing to the inlet valves 80 of the pump cylinder. Thence the charged air is pumped through the delivery valves *n* to the pipe *o* bent upwards to a height above the level of the liquor in the washing machine and connected to the pipes *p* which 85 enter the machine at or near the bottom, well below the bulk of the liquor in the vessel. The liquor moreover is preferably maintained constantly in agitation so as to retard the escape of the charged air and vapors.

q is a discharge cock for the receptacle *j* and *r* is an overflow to prevent the receptacle from being overfilled. The receptacle for the vapor yielding substance need not necessarily form part of the pump casing as 95 shown but may be arranged separately therefrom if preferred.

The vapor or volatile substance will be selected according to the material being treated and the nature of the treatment in progress; for instance, when articles of vegetable fiber are to be washed, volatile vegetable oils may be used, such as turpentine. Some of these oils have the property of absorbing oxygen from the air which being again liberated in an active state in the washing solution aids the vapors of the oil in cleansing the goods.

Carbon-tetra-chlorid can be employed in cleansing woolen, hair and silken goods and will be found to be extremely useful in removing certain stains and grease. Other 5 volatile substances may also be employed.

What I claim is:

A process of washing linen, woolen and other fibrous materials consisting in placing the goods to be washed in an aqueous wash- 10 ing solution and introducing into the wash-

ing solution while the latter is kept hot and in agitation, an organic detergent in the form of vapor mixed with atmospheric air.

In testimony whereof I have signed my name to this specification in the presence of 15 two subscribing witnesses.

FRIEDRICH LUDWIG BARTELT.
